UNITED STATES PATENT OFFICE.

PAUL HOSSFELD, OF BAD HARZBURG, GERMANY.

VENTILATING-HOOD-LIFTING DEVICE.

1,415,567.

Specification of Letters Patent.

Patented May 9, 1922.

Application filed September 11, 1920. Serial No. 409,750.

(GRANTED UNDER THE PROVISIONS OF THE ACT OF MARCH 3, 1921, 41 STAT. L. 1313.)

To all whom it may concern:

Be it known that I, PAUL HOSSFELD, a citizen of the German Empire, residing at Bad Harzburg, Germany, have invented certain new and useful Improvements in Ventilating-Hood-Lifting Devices, (for which I have filed applications in Germany, April 22, 1916; Austria, April 28, 1917; Czecho-Slovakia, June 28, 1918; Switzerland, June 11, 10 1917, Patent #77894, and Hungary, February 26, 1918,) of which the following is a specification.

My invention refers to ventilator hoods and more especially to an adjusting device 15 for such hoods.

Devices for lifting ventilator hoods in which foldable frame or shears serve as the lifting device and in which tipping over is avoided by means of guides, are already 20 known.

My invention substantially consists in a second frame of links the free joint of which slides in guides, being interposed between the fixed turning point of the lifting device 25 and the movable turning point on the ventilator hood to be lifted.

In comparison with similar devices already known my new adjusting device has the advantage that it requires materially shorter 30 guides, in order to give sufficient security against tipping over, and does not require special hoods for protection against rain.

In the drawings affixed to this specification and forming part thereof, different 35 modifications of a lifting device for ventilator hoods embodying my invention, are illustrated by way of example. In the drawings—

Fig. 1 is an elevation of one modification, 40 Fig. 2 being a vertical cross-section.

Figs. 3 and 4 are diagrams of different modifications.

Referring to Figs. 1 and 2 of the drawings the new device consists of a shears 45 formed by four shanks *a*, the lower linking point *b* of which is connected to a fixed part *c* of the roof construction, whilst the upper linking point *d* is attached to the ventilator hood *e* to be shifted. Between the shanks *a* 50 of the shears a frame of links *d*, *f*, *g*, *h*, is provided, the lower linking point *g* of which slides in guides *i*, thus securing the shears *a* with the ventilator hood *e* against tipping.

The one lower shank *a* of the shears is extended beyond the lower linking point *b* so 55 as to form the bar *k* which is provided with a counterweight *l* which balances the weight of the ventilator hood *e* tending to collapse the shears *a*. Extending the shears and the consequent lifting of the ventilator hood is 60 effected by exerting tension or pressure on the rod *k*. In the modification illustrated by way of example, in Figs. 1 and 2 the bar *k* is not connected to the traction element (traction rod *m*) effecting the adjustment, directly, but under insertion of two bars *n* and *o* forming a triangle with the bar *k*. In this manner the traction rod *m* 65 is only required to perform a much smaller vertical motion in raising and lowering the 70 ventilator hood *e* than if it acted directly upon the end of the rod *k*. Besides that, the tensile force acts in a pressing sense upon one of the intermediate linking points of the shears *a* through the agency of the bar 75 *n* in an advantageous manner.

The foldable frame serving as a guide may also be arranged so as to have a different common linking point with the shears *a* than the one (*d*) selected in Fig. 1. Fig. 80 3 is an arrangement of the foldable frame which is symmetrical to that of the preceding modification, the fixed turning point of the shears being here chosen as the common linking point.

Fig. 4 is a further modification of the invention in which the foldable frame is arranged at the side in relation to one of the intermediate linking points *p*. A point to be noted in connection with this modification consists in its being possible to omit the shanks of the shears dotted in in the drawing, without the effect of the device being impaired. The shears forming the lifting device are thus converted into a simple 85 90 95 toggle lever.

I claim:

1. In a device of the kind described in combination, a foldable frame having a fixed linking point, links pivoted to two adjoining arms of said frame and having their free ends pivoted to each other and a vertical guide for guiding said free ends and means for operating said frame. 100

2. In a device of the kind described in 105 combination, a foldable frame having a

fixed linking point, links forming with two adjoining arms of said frame, another foldable frame and means for guiding the free linking point of said latter frame in a vertical direction and means for operating said first frame.

3. In a device of the kind described in combination, a foldable frame having a fixed linking point, links forming with two adjoining arms of said frame another foldable frame and means for guiding the free linking point of said latter frame in a vertical direction, one arm of the first frame being prolonged beyond its linking point and a counterweight on said arm, and means for operating said first frame.
- 10 4. In a device of the kind described in

combination, a foldable frame having a fixed linking point, links forming with two adjoining arms of said foldable frame another foldable frame and a means for guiding the free linking point of said latter frame in a vertical direction, one arm of the first frame being prolonged beyond its linking point, a counterweight on said arm, means for moving said prolongation and a rigid connection between said moving means and the free ends of said arm and its prolongation respectively.

20 25 In testimony whereof I affix my signature. 30
PAUL HOSSFELD.
